UNITED STATES PATENT OFFICE.

EVERETT H. BARNEY, OF SPRINGFIELD, MASSACHUSETTS.

HOCKEY-GAME SKATE.

SPECIFICATION forming part of Letters Patent No. 605,285, dated June 7, 1898.

Application filed December 3, 1897. Serial No. 660,607. (No model.)

To all whom it may concern:

Be it known that I, EVERETT H. BARNEY, a citizen of the United States of America, residing at Springfield, in the county of Hampden and State of Massachusetts, have invented new and useful Improvements in Hockey-Game Skates, of which the following is a specification.

This invention relates to skates, and to a peculiar construction thereof which adapts them to the use of skaters in playing the game of "hockey," so called, upon the ice, the object being to provide an improved sole-plate for said skates; and the invention consists in the combination, with a skate-runner and heel connections thereon, of a sole-plate attached to said runner containing said improvements, all as hereinafter described, and more particularly pointed out in the claims.

In the drawings forming part of this specification, Figure 1 is a plan view of the upper side of a skate having a sole-plate thereon embodying my improvements. Fig. 2 is a plan view of the under side of the skate, illustrating the same applied to the sole of a shoe as it first appears after such application. Fig. 3 is a plan view of the under side of a portion of the sole-plate of the skate, illustrating a manner of providing an exchangeable part or parts therefor, as below set forth.

Referring to the drawings, A is the runner of the skate. B B are the heel-brackets firmly secured on opposite sides of said runner by rivets passing transversely through the legs 35 of the brackets and the runner, as shown, or by other suitable means. Said heel-brackets are perforated, as shown, so that the screws 8 may be inserted through them for screwing into the shoe-sole P, as shown in Fig. 2, where- 40 by the rear end of the skate is secured to the sole of a boot or shoe.

D indicates the sole-plate of the skate, of sheet-steel, preferably, or of such metal as best fits certain parts of the plate, to serve as a substitute runner for temporary use in place 45 of said runner A in the said game of hockey. The outline form of said sole-plate is made to conform more or less to that of a shoe-sole on which the skate is worn for skating. The 50 sole-plate has suitable perforations through which to pass screws 7 for securing the same to a shoe-sole, and the heel-brackets B are

similarly secured to the heel of the shoe by the screws 8. The said game of hockey, for playing which the within-described skate is 55 constructed, requires for playing the same most efficiently and conveniently a runner-section on one or both borders of the sole-plate, which serves in place of the long runner A at certain times, as follows: Said game 60 involves the most rapid movements of the skater upon the ice in such circles as are unavoidable when he is compelled to turn abruptly from a right-line movement to run off laterally or in an opposite direction, and such 65 evolutions cannot be satisfactorily performed upon the usual full-length skate-runner A on account of the too-extended ice-contact which the latter has. Therefore the within-described improved sole-plate construction is 70 provided, on which is one or more substitute runner-sections C C², the latter indicating the section on the inner edge of the sole-plate. The outer border of each of said substitute runner-sections is sufficiently sharpened to 75 cause it when brought upon the ice to so engage therewith as to make it to follow the circular line of movement which the skater's foot directs without danger of slipping on the ice. Thus when the above-described evolu- 80 tions are performed the skater turns his foot to such an extent as brings the edge of said runner-sections against the ice, and in so doing the runner proper, A, of the skate is lifted clear from the ice, and momentarily the said 85 section performs the function of the usual skate-runner, but under the said conditions peculiar to said game. It is sometimes found convenient to have said substitute runner-sections (one or both) removable or exchange- 90 able, either for obtaining a change of form, for sharpening, or other cause, and to meet said convenience provision is made, as illustrated in Fig. 3, for making said runner-sections separate from the sole-plate and securing them at the border of the latter, so that the outer edge thereof will sufficiently project 95 beyond the shoe to engage, as aforesaid, with the ice. In said last-named figure, 10 is the substitute runner-section, 9 is the sole-plate, 100 and P indicates a part of a shoe-sole.

In Fig. 3 of the drawings the exchangeable runner-section 10 is shown secured to a part of the shoe-sole with its inner edge abutting

the outer edge of the sole-plate 9. It is obvious, however, that said section 10 may, if preferred, be secured directly onto the under side of the sole-plate.

5 Having thus described my invention, what I claim, and desire to secure by Letters Patent, is—

1. In a skate of the class described, a sole-plate therefor having on one edge thereof a laterally-projecting substitute runner-section, substantially as and for the purpose set forth.

10 2. In a skate of the class described, a sole-plate therefor having on its opposite edges

laterally-projecting substitute runner-sections, integral therewith, substantially as set forth.

15 3. In a skate of the class described, a sole-plate therefor combined with one or more exchangeable substitute runner-sections, and 20 means for securing said section or sections at the outer border of said sole-plate, substantially as set forth.

EVERETT H. BARNEY.
